UNITED STATES PATENT OFFICE.

ROBERT F. KURZ, OF NEW HAVEN, CONNECTICUT, ASSIGNOR OF TWO-THIRDS TO FRED A. DAMON AND ONE-THIRD TO FRANK STARITA, BOTH OF NEW HAVEN, CONNECTICUT.

BOX-NAILING MACHINE.

Application filed April 18, 1923. Serial No. 632,912.

This invention relates to nailing and similar fastening machines, and is particularly adapted to devices wherein boxes of various sizes and shapes may be rapidly and conveniently nailed together. It is so arranged that a number of nails can be driven at one operation, and while there is provided a device which presents a great saving in labor over handwork, at the same time, the machine is relatively simple in construction and operation and made of a comparatively small number of parts, and, for that reason, comparatively inexpensive.

One object of my invention is to provide a horizontal box nailing machine of a simple nature, in which the nails may be driven in a satisfactory manner.

Another object of my invention is to provide a box nailing machine of the character described, having a nail support disposed at a slight angle to the horizontal, so that the nails will be driven in an exactly horizontal direction.

A still further object of my invention is to provide a new and improved means for delivering the nails to be driven in front of the hammers, one at a time, and in a satisfactory manner and position.

My invention further contemplates the provision of adjustment in various parts of the device, whereby boxes of different sizes may be conveniently handled, and whereby the nails may be driven at various spaced distances.

To these and other ends, the invention consists in the novel features and combinations of parts to be hereinafter described and claimed.

In the accompanying drawings:

Fig. 1 is a perspective view of my improved machine;

Fig. 2 is a rear elevational view of the same;

Fig. 3 is a fragmentary, perspective view of the upper portion of the device, showing the nail hopper;

Fig. 4 is a sectional view on line 4-4 of Fig. 3;

Fig. 5 is an enlarged fragmentary detail view of the nail picking mechanism;

Fig. 6 is a sectional view on line 6-6 of Fig. 2, looking downwardly;

Fig. 7 is a sectional view on line 7-7 of Fig. 6, showing the parts at the beginning of the nail driving operation;

Fig. 8 is a view similar to Fig. 7, showing the position of the parts at the completion of the nail driving operation;

Fig. 9 is a sectional view on line 9-9 of Fig. 6;

Fig. 10 is a sectional view on line 10-10 of Fig. 6;

Fig. 11 is an enlarged sectional view, showing the position of the nail driving parts at the beginning of the nail driving operation;

Fig. 12 is a similar view, showing the position of the parts after the nails have been driven.

In the preferred form of my invention illustrated in the drawings, I have shown a frame consisting of a pair of side standards 10 and 11, upon which is carried a table 12. Upon the table 12 are mounted two upper standards 13 and 14, which serve to support various parts of the mechanism, as will be hereinafter described. The standards 10 and 11 may be connected by tie rods 15 and 16, and upon one of these standards is mounted a stud-shaft 18, which carries a rocking treadle 19 connected by a link 20 to a single-action clutch 21, mounted upon a crank shaft 22 rotatably carried in suitable journals 23 and 24 upon a cross-piece 25, which constitutes a part of the frame.

In suitable journals 26 and 27, depending from the table 12 is carried a rock shaft 28 upon which is rotatably or loosely mounted a pulley wheel 29, which may receive power from any suitable source, and to the hub of which is rigidly secured a pinion 30. This pinion is in mesh with a gear 31 loosely mounted on the crank shaft 22 and adapted to be secured thereto by the clutch 21, which, when actuated by the treadle, clutches the gear to the crank shaft to cause a single revolution of the latter, and then is automatically disengaged.

The crank 32 of the crank shaft 22 is connected by a link 33 to a crank arm 34 on the rock shaft 28, so that the latter will be oscillated upon the rotation of the crank 22. The oscillations of this shaft, in the form of my invention shown in the drawings, accordin-

plishes the mechanical operations of delivering the nails to the driving mechanism and driving them into the work.

In suitable guide ways in the table 12 is 5 slidably or reciprocably mounted a work carrier 36. At the rear edges of the carrier are mounted a pair of standards 37, between which is carried a bar 38 against which the work is adapted to abut. There is also 10 mounted in extensions 39 and 40, upon the work carrier, a swinging nail support or guide 41. In the extensions 39 and 40 are provided suitable pins or trunnions 42 which 15 project into sockets or bearing brackets 43 attached to the rear side of the nail support. This support is made up of two plates, the lower plate 44 carrying the bearing brackets just referred to, and the upper plate 45 being provided with suitable nail guiding 20 grooves 46. These grooves are cut entirely through the surface of the plate, so that the nail is suitably guided into the work thereby. The upper plate of the nail guide may 25 be secured to the lower plate by suitable bolts or screws, as shown in Figs. 7 and 8, so that the inclination of one of these plates relative to the other may be adjusted.

To the lower surface of the plate 44 is secured a strap 47, which is provided with a 30 substantially horizontally disposed rear end portion 48 and an inclined portion 49 extending inwardly therefrom. These parts of the plate are adapted to cooperate with an adjustable stop 50 secured to the intermediate 35 portion of a plate 51 mounted upon the table 12, the end of the strap passing through an opening 51^a in this plate below the stop 50. The adjustability of the stop 50 is, in this instance, secured by having an 40 elongated opening therein, and a screw passing through this opening into the plate 51. From an inspection of Fig. 7, it will be apparent that when the work carrier 36 is 45 moved rearwardly, the nail being, of course, carried with it, this guide will be permitted to drop from its inclined position, shown in Fig. 7, to a substantially horizontal position, shown in Fig. 8, due to the fact that the stop 50 will be permitted to ride along the inclined surface 49 of the cam plate 47.

In the device illustrated, I have preferred 55 to produce the relative movement between the work and the nail driving members by holding the latter in a stationary position and moving the work toward them. I effect 60 this operation by a movement of the work carrier 36, and this is accomplished by providing an abutment 55, which lies along the top of the work carrier and which is secured to a pair of rods 56 and 57, which, at their 65 rear ends, are secured to sleeves 58 and 59, connected by the rock arms 60 and 61 to the crank shaft. It will be apparent that when the shaft 28 is rocked by the link 33, the rock arms 60 and 61 will tend to pull the

rods 56 and 57 rearwardly, and will likewise draw the abutment 55 toward the machine. If a box is being nailed and this box lies in a closely fitting position between the abutment 55 and the stop rail 38, the movement of the rods 56 and 57 will be imparted to the work carrier 36 through the box and through the stop rail, so that the work carrier, together with the swinging nail guide 41, will all be moved rearwardly. The abutment 55 is adjustably secured upon the rods 56 and 57 by providing these rods with threads throughout their length and adjustably securing the nuts 62 upon each side of the abutment 55. It is in this manner that 75 boxes of different sizes may be accommodated.

The return of the work carrier to its forward position, shown in Fig. 1, is accomplished, as shown more particularly in Fig. 6, by the provision of the pins 65 and 66 secured to the sleeves 58 and 59 and arranged to engage the rear edge of the work carrier, so as to push it outwardly to position to begin another operation. 85

At the upper ends of the standards 13 and 14, a nail hopper 67 is rockably mounted and is provided with slots 68 in the bottom thereof, through which the bodies of the nails are adapted to project, the slots being provided at their forward ends with broadened or enlarged portions 69 through which the nail heads may pass. The hopper is reciprocated by means of a crank arm 70, provided upon the rock shaft 28 and connected by a link 71 to a bail 72 connected to the hopper. 90

When the nails fall from the slots 68, they drop upon inclined nail guides 73, as shown in Figs. 3 and 4, and slide downwardly in these guides to the lower end thereof, where 105 they rest against transversely disposed picking fingers 74 of the nail picker. This nail picker comprises a transverse member composed of two plates 75 and 76, which are reciprocably mounted in the standards 13 and 14. Between these two plates are secured the nail picking fingers, one for each nail guide 73, which fingers consist of a longitudinally extending portion 74' secured between the plates 75 and 76, and the transversely extending portion, which has already been referred to. 110

When the nail picker is reciprocated, the picking fingers 74 move to the left and permit a nail to move out of engagement with the same from each of the nail guides 73, and into engagement with the inner edge of the plate 75 where the nails are retained until the nail picker is moved to the right. When this movement takes place, the opening 77 provided in the plates 75 and 76, as well as in the plate or frame member 78, are aligned to permit the nail to drop into flexible tubes 80, as seen in Fig. 5. Nipples 79 are provided within the openings 77 of the 125 130

frame member 78, in order that the tubes 80 may be readily assembled thereto. The frame member 78 is secured to the side frames 13 and 14, and acts as a tie bar for the same, whereby the side frames are rigidly braced. The nails so released pass downwardly to the flexible tube 80 to the delivery chutes 81, from which they drop into the grooves 46 formed in the swinging nail guide 41. During the passage from the inclined nail guide 73 to the swinging nail guides 41 the nail is turned from a vertical position with its point extending downwardly to a horizontal position and with its point extending outwardly toward the front of the machine.

The reciprocation of the nail picker is effected through a bell crank 82 pivoted at 83, having one end connected to the picker bar 75 and the other end pivotally connected to a rod 84 reciprocably mounted on the frame 13, and carrying at its lower end a friction roller 85 which is engaged by the surface 86 of a cam mounted upon one of the standards 37 of the work carrier, as shown more particularly in Fig. 10. It will be apparent that when the work carrier is moved toward the frame of the machine, the rod 84 will be moved upwardly, due to its being caused to ride upon the cam surface 86, and the nail picker will be reciprocated through the bell crank 82, which is returned by the action of a spring 84^a connected, at its upper end, to the bell crank, and, at its lower end, to the frame 13.

A shield or guide 87 may be provided to prevent the heads of the nails catching on the edges of the nipples 79, so that they may make sure and speedy progress from the nail picker to the delivery chutes 81. These chutes are connected to the flexible tubes 80 and are loosely mounted upon a transversely extending shaft 90, which shaft is carried by a pair of side brackets 91 pivotally mounted at 92 upon ears 93 on the side standards 37. A spring 94 urges these brackets in a counter-clockwise direction, as shown in Fig. 9, and the free arm 95 thereof bears against the upper side of the swinging nail guide 41. The delivery chutes 81 may be freely moved transversely of the machine along the shaft 90 to adjust them to positions above the proper nail guiding grooves 46. It is by this means that the nails may be driven at variously spaced points in the work.

The nails are driven by means of the hammers 100, which are secured by means of collars 101 to a rock shaft 102, mounted in suitable bearings in standards 103 secured to the plate 51. A spring 104 tends to urge this shaft in a counter-clockwise direction, as shown in Fig. 10, and tends to hold the hammers upon the surface of the swinging nail guide 41. By loosening set screws 105 in the collars 101, the hammers

can be adjusted longitudinally of the shaft 102, and can be arranged to suit the desired spacing of the nails.

From the foregoing description, the following operation of the machine upon a predetermined size and style of box or other work is obvious. The abutment or clamping bar 55 is properly adjusted relative to the rail 38 or the class of work to be operated upon, after which power is applied by means of the foot-pedal 19. Movement of the gearing and connecting levers immediately starts and by its connection with the connecting rods 56 and 57, the abutment 55 forces the work against the rail 38 and retains it in clamped position thereagainst. The movable work carrier 36 is caused to move rearwardly by a continued movement of the abutment 55. The work, therefore, is forced against the nails which are lying in the grooves 46, and retained against rearward movement by the hammers 100. During the latter part of the rearward movement of the work carrier 36, the nail hopper is agitated and the nail pickers are reciprocated to the left. After the work carrier 36 and the work thereon has been moved to the extreme rearward position, a continued operation of the machine releases the bar 55 from its clamping engagement with the work, allowing the work to be removed, and subsequently the pins 65 and 66 engage the work carrier 36 to move the same forwardly. The movement of the work carrier 36 forwardly causes the cam 86 mounted thereon to reciprocate the nail picker to the right, thereby releasing another series of nails which drop into their respective chutes and are directed into position in the proper grooves 46. When the nail is lying horizontally upon the swinging nail guide 41, it will be obvious that, as shown in Fig. 11, the nail head would, if the carrier were exactly horizontal, cause the nail to point downwardly, so that it would not be driven in a horizontal position. To avoid this the carrier is given a slight upward tilt, due to the engagement of the plate 48 by the stop 50, and the nail is caused to lie in a truly horizontal plane. As the table moves rearwardly, the strap 47 moves rearwardly until the stop engages the inclined surface 49, and the swinging nail carrier is permitted to assume a horizontal position, so that the nail may be completely driven into the work in the proper position. By adjusting the stop 50, the swinging nail support can be caused to assume different inclinations relatively to the horizontal and can, in this way, be adjusted to accommodate nails having different sized heads and to drive them in an exactly horizontal position.

The single-action clutch 21, as has already been stated, connects the gear 31 to the shaft 22 to cause a single rotation of the shaft at

each actuation of the treadle, and this, in turn, effects a complete cycle of the operation of the machine. The work carrier is not only drawn toward the hammers to cause the nails to be driven into the work, but it is also returned to its original position, the swinging nail support being then moved from the positions shown in Figs. 8 and 12 to the positions shown in Figs. 7 and 11, whereupon another nail drops from the delivery chute 81 into the grooves 46 in front of the drivers 100, and the parts are then in position to begin another operation.

While I have chosen to illustrate a machine in which the nails are driven by a movement of the work relatively to the drivers, it will be understood that this arrangement is not important in all aspects of the invention and the same result might be obtained by moving the drivers toward the work. It is, of course, the relative movement of the work and drivers that effects the driving of the nails, and a reversal of parts may be resorted to without departing 25 from the spirit of the invention.

While I have shown and described a preferred embodiment of my invention, it will be understood that it is not to be limited to all the details shown, but is capable of modification and variation within the spirit of the invention and within the scope of the appended claims.

What I claim is:

1. In a nailing machine, a work carrier, 35 a nail support, means to drive the nails into the work, a cam plate secured to said support, and adjustable means cooperating with said cam plate to control said support whereby the nail body is held in horizontal position at the beginning of and during the nail driving operation.

2. In a nailing machine, a work carrier, a nail support, means to drive the nails into the work, a cam plate secured to said nail 45 support, and adjustable means cooperating with said cam plate to automatically adjust the inclination of the nail support during the nail driving operation.

3. In a nailing machine, a frame, a work 50 carrier movably supported thereon, a nail support movably mounted on said work carrier, means to drive the nails into the work, and adjustable means mounted on the machine frame to cooperate with a part of said nail support to vary the positions thereof during the nail driving operation.

4. In a nailing machine, a work carrier, a nail support, means to drive the nails into the work, a cam plate secured to said nail 60 support, and adjustable means cooperating with said cam plate to adjust the inclination of the nail support at the beginning of the nail driving operation and to automatically adjust the same during the nail driving operation.

5. In a nailing machine, a frame, a work carrier slidably mounted thereon having a nail guide associated therewith, means to deliver a nail to said nail guide, means to drive the nail into the work comprising a movable abutment and a relatively stationary hammer, said abutment adapted to clamp the work against a portion of said work carrier whereby said work carrier and its associated nail guide is moved toward 70 said hammer, and common means to move said abutment into and out of such clamping position and subsequently to move said carrier away from said hammer.

6. In a nailing machine, a frame, a work carrier slidably mounted thereon, a tiltable nail guide pivotally secured to said carrier, resilient means to retain said nail guide in a horizontal position, means to deliver a nail to said nail guide, nail driving means relatively stationary with respect to said carrier, and adjustable means to tilt the nail guide a predetermined amount whereby the body of the nail is held in a horizontal position before driving and to allow the return of said nail guide to its horizontal position during the driving operation to insure the continued horizontal position of said nail body.

7. In a nailing machine, a frame, a work carrier slidably mounted thereon, a tiltable nail guide pivotally secured to said carrier, said nail guide normally lying in a horizontal plane, means to deliver a nail to said nail guide, nail driving means relatively stationary with respect to said carrier, and adjustable means to tilt the nail guide whereby the body of the nail is held in a horizontal position before driving and to allow the return of said nail guide to its 100 normal position during the driving operation to insure the continued horizontal position of said nail body.

8. In a nailing machine, a frame, a work carrier slidably mounted thereon, a nail guide tiltably secured to said carrier, means to deliver a nail to said nail guide, nail driving means relatively stationary in respect to said carrier, means to clamp the work against a portion of said carrier, said clamping means being adapted to move said carrier toward said driving means when the work is clamped thereby, whereby the nail is forced from said nail guide into the work by said nail driving means, and means associated with said nail guide for tilting the same during the nail driving operation, whereby the nail body is held in a horizontal position.

9. In a nailing machine, a frame, a work carrier slidably mounted thereon, a nail guide tiltably secured to said carrier, means to deliver a nail to said nail guide, nail driving means relatively stationary in respect to said carrier, means to clamp the work 125

against a portion of said carrier, said clamping means being adapted to move said carrier toward said driving means when the work is clamped thereby, whereby the nail 5 is forced from said nail guide into the work by said nail driving means, means associated with said nail guide for tilting the same during the nail driving operation, whereby the nail body is held in a horizontal position, and means associated with said carrier 10 and operable in timed relation to the movement thereof whereby another nail is delivered to said nail guide after the return of said carrier and work clamping means to 15 their inoperative position.

10. A box nailing machine, wherein there is provision for movement of the work toward the nail driving means, including a driven clamping bar for clamping the work 20 against a portion of a slidable work carrier, whereby said work carrier is moved toward the nail driving means, means to operate said clamping bar, said means being adapted to move said bar into unclamped position 25 and to subsequently move said carrier away from said nail driving means, a nail guide, and means to deliver a nail to said nail guide during the operation of the machine, but before said carrier is moved toward the 30 nail driving means.

11. In a nailing machine, a movable work carrier, nail driving means relatively stationary with respect thereto, a nail guide movable with said carrier, means to deliver 35 nails to said nail guide, means to move work upon said work carrier into clamped engagement therewith, said work moving means capable of continued movement thereafter in the same direction whereby said carrier, said nail guide, and said nail driving means are operated to cause a nail to be forced from said nail guide into the work and means to actuate said work moving means, said actuating means adapted to move said work moving means out of clamping engagement after the nail driving operation is completed, and to subsequently move 45 said carrier away from the nail driving position.

50 12. In a nailing machine, a movable work carrier, nail driving means relatively stationary with respect thereto, a positively controlled tiltable nail guide movable with said carrier, means to deliver nails one at a time to said nail guide, means to move work upon said work carrier into clamped engagement therewith, said means capable of continued movement thereafter in the same direction whereby said carrier, said nail guide, and said nail driving means are operated to cause a nail to be forced from said nail guide into the work, and means to operate said work moving means, said operating means being adapted to move said work moving 55 means and subsequently to move said car-

rier away from said nail driving means, said nail delivering means being operable by the movement of said carrier away from said driving means to deliver a nail to said nail guide. 70

13. In a nailing machine, a movable work carrier, nail driving means relatively stationary with respect thereto, a positively controlled tiltable nail guide movable with said carrier, means to deliver nails to said nail guide, adjustable means to tilt said nail guide, and means to move work upon said work carrier into clamped engagement therewith, said means capable of continued movement thereafter in the same direction, 80 whereby said carrier, said nail guide, said nail driving means, and said nail guide tilting means are operated to cause a nail to be forced from said nail guide, with its body lying parallel with the direction of driving, 85 into the work.

14. In a nailing machine, a frame having a slidable work carrier and a relatively stationary nail driving means mounted thereon, means to move work against a portion of said work carrier to clamp the same thereagainst and subsequently to move said work carrier toward said driving means, and means to operate said work moving means, said operating means adapted to move said work 90 moving means out of clamping engagement and subsequently to move said carrier away from said driving means. 95

15. In a nailing machine, a frame having a slidable work carrier and a relatively stationary nail driving means mounted thereon, means to move work against a portion of said work carrier to clamp the same thereagainst and subsequently to move said work carrier toward said driving means, means 100 to support a nail in position for engagement by said nail driving means, said nail supporting means being secured to and movable with said carrier, and means to tilt said nail supporting means during the nail driving operation thereby holding the body of the nail in a horizontal position during the driving operation, said tilting means being adjustable to vary the amount of tilting of said supporting means proportional to the 105 diameter of the heads of various nails. 110

16. In a nailing machine, means to drive a nail by the relative movement of a nail driving member and a work carrier, a pivotally mounted nail guide adapted to receive the nail to be driven, and means to automatically adjust said nail guide during the nail driving operation whereby the nail is directed into the work at a predetermined angle relatively thereto. 115 120

17. In a nailing machine, means to drive a nail by the relative movement of a nail driving member and a work carrier, a tiltable nail guide adapted to receive the nail to be driven, and means to automatically 125 130

- vary the amount of tilting of said nail guide, during the nail driving operation, whereby the nail is directed into the work at a predetermined angle relatively thereto.
- 5 18. In a nailing machine, means to drive a nail by the relative movement of a nail driving member and a work carrier, a tiltable nail guide adapted to receive the nail to be driven, and means to automatically and uniformly vary the amount of tilting of said

nail guide during the nail driving operation, whereby the nail is directed into the work at a predetermined angle relatively thereto, said means being adjustable whereby the nail guide is adapted for use with varied sizes of nails. ¹⁵

In witness whereof, I have hereunto set my hand on the 17th day of April, 1923.

ROBERT F. KURZ.
